ATTACHMENT PLUG RECEPTACLE

George A. Johnson, Fairfield, Conn., assignor to
 The Bryant Electric Company, Bridgeport,
 Conn., a corporation of Connecticut

Application July 15, 1931, Serial No. 550,969

15 Claims. (Cl. 173—330)

This invention relates to attachment plug receptacles. More particularly, this invention relates to duplex attachment plug receptacles in which the contacts of the two outlets are adapted to be fed from separate feed lines. One of the many instances of the utility of this device is in a kitchen where an electric refrigerator and an electric iron are to derive current through the same receptacle. If both outlets were fed from the same branch circuit of the power system that circuit might, when both the refrigerator and iron were drawing current, become overloaded. When the outlets are fed separately, that is by different branch circuits, the difficulty of overloading is removed.

It is an object of this invention to make a simple and compact contact construction for a receptacle of the above type, which can be assembled in the receptacle quickly and easily.

Other objects and advantages of the invention will appear as it is described in connection with the accompanying drawing.

In the drawing:—

Fig. 1 is a view of a receptacle embodying my invention, looking into the receptacle from the rear when the rear cover and supporting strap are partly broken away.

Fig. 2 is a side view of the receptacle shown in Fig. 1.

Fig. 3 is an exploded view of one of the contacts used in the receptacle.

Fig. 4 is a side view of the contact shown in Fig. 3, assembled.

Fig. 5 is a perspective view of the insulating member of the contact assembly.

Fig. 6 is a perspective view of a modified form of member for insulating and joining the contacts of my invention.

Referring to the drawing, the receptacle comprises a hollow insulating casing 10, having a spine 12, running up its middle, four conventionally located and spaced T-shaped contact slots 14 in its front face (bottom as seen in Fig. 1) and recesses 16 in its side walls to accommodate the wire terminals 18 of the receptacle contact assemblies, which will hereinafter be described. The receptacle has a rear cover plate 20 of sheet insulation which holds the contacts in place and is itself held in place by the conventional supporting strap 22 of the receptacle in the customary manner.

The receptacle has two contact assemblies which are identical and interchangeable. Description of one will therefore suffice. Each contact assembly is made of a number of compo-

nent parts including two metallic strips 25 which are bent laterally at right angles, as at 27, midway of their lengths and again bent laterally in U-formation as at 29, leaving a tail which presses against the spine 12. One edge of each of these contacts is flush with the plane of the rear of the receptacle and lies against and is supported by the rear cover plate 20. Contact fingers 33, 35 project up from the bent portions of the contacts 25 toward the front of the receptacle and adjacent the T-slots 14, for engagement by the prongs (not shown) of an attachment plug cap as they are inserted in the slots 14. The ends of the straight portions of the contacts have portions 37, extending forwardly of the receptacle, forming wire terminals. The free ends 38 of these wire terminals are bent approximately 45° from the plane of the terminals for a purpose as will hereinafter appear.

Joining the contacts together in insulated relation are a pair of angles, 40, a plate of insulation 42 and two hollow, square headed rivets 44. The angles may be conveniently punched from a sheet of fibrous insulation and bent into angular form as shown in Fig. 5. These angles are fitted together back to back with their abutting portions 40a projecting between the ends of the contacts 25 and their oppositely directed portions 40b lying behind the terminals 37. The insulating plate 42 lies behind the portions 40b and is of such size as to be in substantial registry with the edges of the portions 40b when the portions 40a are back to back. Thus, this plate joins the contact 25 and angle 40 at one end of the contact assembly to the angle and contact at the other end.

The component parts of the contact assembly are secured together by the hollow rivets 44 which pass through registering holes 48 in the contacts 25, angles 40b, and plate 42. These rivets are internally threaded to receive terminal screws 50.

There are extensions 40c projecting forwardly of the receptacle from the portions 40a of the angles 40, between the inclined portions 38 of the wire terminals 37. It may now be seen that the function of these inclined portions 38 is to keep the portions 40a of the angles 40 perpendicular to the wire terminals 37.

It will be observed that by having square heads on the rivets 44 with one edge of the head lying adjacent the insulating barrier formed by portions 40a of angles 40 any tendency of the rivets to rotate as the binding screws 50 are turned into the rivets, will be overcome. Thus even if the rivets should become slightly loosened the contact assembly would stay intact and function perfectly.

In Fig. 6 I have shown a modification of my invention wherein the insulating plate 42 and angles 40 are unitary. This unitary member may be made of molded insulation, but I prefer the stronger construction made of two pieces of fibre as shown in Fig. 5.

From the foregoing it will be apparent that I have provided a compact contact assembly the parts of which may be cheaply manufactured and 10 easily assembled in the receptacle.

Many modifications will occur to those skilled in the art, therefore I do not limit my invention to the specific embodiment shown.

I claim:—

15. 1. A contact assembly for a duplex attachment plug receptacle, comprising metallic members having contact portions and wire terminals, a pair of angle members made of insulating material, an insulating member joining said metallic members, a pair of hollow rivets securing said metallic members to said insulating member, said rivets having non-circular portions to prevent their being rotated, said angle members being secured back-to-back between said metallic members by said rivets, and binding screws threaded into said rivets.
20. 2. A contact assembly for an attachment plug receptacle having a plurality of outlets, comprising metallic members having contact portions and wire terminals, angle members of insulating material, an insulating member joining a pair of said metallic members, hollow rivets securing said pair of metallic members to said insulating member, a pair of said angle members being secured 30 back-to-back between said pair of metallic members by said rivets, and binding screws threaded into said rivets.
25. 3. A contact assembly for an attachment plug receptacle having a plurality of outlets, comprising metallic members having contact portions and wire terminals, angle members of insulating material, an insulating member joining a pair of said metallic members, rivets securing said pair of metallic members to said insulating member, a 35 pair of said angle members being secured back-to-back between said pair of metallic members by said rivets.
30. 4. A contact assembly for an attachment plug receptacle having a plurality of outlets, comprising metallic members having contact portions and wire terminals, angle members of insulating material, an insulating member joining a pair of said metallic members, means securing said pair of metallic members to said insulating member, a 40 pair of said angle members being secured back-to-back between said pair of metallic members by said rivets.
35. 5. A contact assembly for an attachment plug receptacle having a plurality of outlets, comprising metallic members adapted to be located at opposite ends of a receptacle and on the same side thereof, said metallic members each having a contact portion and a substantially flat wire terminal portion, insulating means having a portion perpendicular to and between said wire terminal portions and insulating them from one another, and means securing said metallic members together in insulated relation, said assembly being insertable in said receptacle as a unit.
40. 6. A contact assembly for an attachment plug receptacle having a plurality of outlets, comprising metallic members having contact portions and wire terminals, an insulating member for joining said metallic members, an angle member insulating said metallic members, and means

securing said metallic members, insulating member and angle member together.

7. A contact assembly for an attachment plug receptacle having a plurality of outlets, comprising metallic members adapted to be located at opposite ends of a receptacle and on the same side thereof, said metallic members each having a contact portion and a wire terminal portion, an insulating member for joining said metallic members, said insulating member having a laterally extending portion between said metallic members and insulating them from each other, and means securing said metallic members to said insulating member.

8. A contact assembly for an attachment plug receptacle having a plurality of outlets, comprising metallic members each having a contact portion and a wire terminal portion, an insulating member having a portion lying between and insulating said metallic members, said wire terminal portions having inclined portions tending to maintain said portion of said insulating member in a position perpendicular to the plane of said wire terminals.

9. A contact assembly for an attachment plug receptacle having a plurality of outlets, comprising metallic members adapted to be located at opposite ends of a receptacle and on the same side thereof, said metallic members each having a contact portion and a wire terminal portion, angle members insulating said metallic members, and means securing said metallic members and angles together, whereby the assembly may be inserted in the receptacle as a unit.

10. A contact assembly for an attachment plug receptacle having a plurality of outlets, comprising metallic members having contact portions and wire terminals, insulating means joining said metallic members and insulating them from one another, said metallic members being secured 40 to said insulating means by hollow rivets internally threaded for the reception of binding screws.

11. A contact assembly for an attachment plug receptacle having a plurality of outlets, comprising metallic members adapted to be located at opposite ends of a receptacle and on the same side thereof, said metallic members each having a contact portion and a wire terminal portion, insulating means joining said metallic members and insulating them from one another, said metallic members being secured to said insulating means by rivets having head portions engaging with said insulating means to prevent said rivets from rotating.

12. An attachment plug receptacle comprising an insulating body having a plurality of outlets, a bottom plate secured to said receptacle, a plurality of metallic members adapted to be located at opposite ends of a receptacle and on the same side thereof, said metallic members each having a contact portion and a wire terminal portion, an insulating member formed separately of said receptacle and insulating certain of said metallic members from each other and extending between the wire terminal portions of certain of said metallic members, and means including said bottom plate for holding said insulating member and metallic members in position.

13. An attachment plug receptacle comprising a recessed insulating body having a plurality of outlets, metallic members each having a contact portion and a substantially flat wire terminal portion, said contact portions lying within said body, insulating means formed separately

- of said receptacle and having a portion perpendicular to and between said wire terminal portions and insulating them from one another, and means for holding said metallic members in fixed position at one side of said body with said perpendicular portion of said insulating means between them.
14. An attachment plug receptacle comprising a recessed insulating body having a plurality of outlets, a bottom plate secured to said receptacle, a plurality of metallic members each having a contact portion and a wire terminal portion, said contact portions lying within said body, a pair of wire terminals on one side of said body formed upon said wire terminal portions, an insulating member formed separately of said insulating body and extending between and insulating the wire terminals of said pair, and means including said bottom plate for holding
- said insulating member and metallic members in position at one side of said body.
15. An attachment plug receptacle comprising an insulating body having a plurality of outlets, a bottom plate secured to said receptacle, a plurality of metallic members each having a contact portion and a substantially flat wire terminal portion, said contact portions lying within said body, a pair of wire terminals on one side of said body formed upon said wire terminal portions, an insulating member formed separately of said insulating body and having a portion perpendicular to and between said pair of wire terminal portions and insulating them from one another, and means for holding said metallic members in fixed position at one side of said body with said perpendicular portion between them. 5 10 15

GEORGE A. JOHNSON.
